EYE GLASS LENS

Joseph M. Kreta, Jermyn, Pa.

Application December 15, 1954, Serial No. 33,569

Term of patent 14 years

(Cl. D57—1)

Fig. 1

Fig. 2

Fig. 1 is a front view of an eye glass lens embodying my new design; and

Fig. 2 is a cross sectional view thereof taken along line 2—2 of Fig. 1.

The characteristic feature of my design resides in the appearance presented by the specific configuration and disposition of the central cut-out portion as viewed in Fig. 1 of the drawing.

I claim:

The ornamental design for an eye glass lens, substantially as shown and described.
